UNITED STATES PATENT OFFICE

1,938,316

REFRIGERATING APPARATUS

Eastman A. Burrows, Chicago, Ill., assignor to
Thomas D. Huff, Chicago, Ill.Application October 13, 1928, Serial No. 141,408
Renewed April 27, 1933

3 Claims. (Cl. 62—99)

My invention relates to refrigerating apparatus and particularly to devices commonly known as refrigerators for use in houses, butchershops, delicatessens and various other places where it is desired to keep articles in a cool place.

One of the objects of the invention is to provide a simple, practical and advantageous refrigerating apparatus of the class specified.

Another object of the invention is to secure 10 refrigeration by artificially produced and maintained ice or ice mats or structures.

Another object of the invention is to arrange for the production of the refrigerating ice or ice structure within the apparatus itself.

Another object of the invention is to provide 15 for the use of natural or loose cakes or pieces of ice temporarily in case the artificially produced ice or ice structure becomes ineffective by melting or otherwise.

Other objects of the invention will be pointed 20 out and appear hereinafter.

In the accompanying drawings:

Fig. 1 is a cross section of a refrigerator especially adapted for butchers or delicatessens and embodying the invention.

Fig. 2 is a cross section taken at right angles to the cross section of Fig. 1.

Fig. 3 is a horizontal section of the device and Figs. 4 and 5 are views of details of construction.

Referring to the drawings I show a refrigerating apparatus in the form of a rectangular box 1, although it is understood that the form or shape of the device may be greatly varied. This box 1 is understood to be of insulating or nonconducting construction in accordance with usual refrigerating box structures. A door 2 is shown for inserting articles within the refrigerator and for withdrawing them therefrom.

Within the box 1 is shown an arrangement by 40 which an ice block or ice mat or other ice like structure is arranged and maintained in a frozen condition. The arrangement shown which of course, can be varied comprises one or more metallic tank like structures 3—3 containing sand 45 or other preferably granular material of relatively high heat conductivity. Water is used in connection with the sand so as to fill the interstices thereof and circulatory pipes 4—4 are imbedded in the sand so as to permit the circulation 50 of a cooling medium in said pipes. By this arrangement the water freezes and with the sand forms an ice mat or icelike structure and the continual circulation of the cooling medium maintains this ice mat or structure in a frozen 55 condition.

These pans or tanks 3—3 may be variously located in the ice box or refrigerator but are preferably mounted well up toward the top of the same so that they may serve as cool or cold surfaces for the support of articles in the refrigerator and may also serve to cool the bottom portion of the refrigerator and thus make it suitable for keeping various articles inserted through the door 2 in a cool condition. 60

As a preferred arrangement the pans 3—3 are 65 made with their outer ends higher as shown in Fig. 1 so as to form outside lips or flanges for holding the frozen material and also the articles thereon in better position. Also drip pans 5—5 are preferably arranged below the pans 3—3. The 70 circulatory pipes 4—4 are preferably connected with suitable apparatus for circulating a cooling medium therein, such, for example, as a refrigerating machine. To such end inlet and outlet pipes 6 and 7 are provided for attachment to 75 such a refrigerating machine and a pipe connection 8 is shown between the pipes 4—4 of the two ice mats, whereby the cooling medium may be circulated through both sets of pipes. Cross beams 9—9 are shown for supporting the tanks 80 3—3 and drip pans 5—5 and other cross beams 10—10 are shown for supporting slats 11—11 which will serve as a floor for holding or supporting articles in case it is desired to place the same thereon. 85

In case the cooling mechanism gets out of order or for other reason the ice mats or structures melt or partially melt so that they cease to be serviceable for the purpose intended, provision is made for permitting the use of ice blocks or 90 pieces as in the ordinary refrigerator or icebox. To such end there is shown a side window or door 12 preferably near the upper part of the box so that pieces of ice may be inserted into the box and placed in position on the floor formed 95 by slats 11 or disposed of otherwise as desired. This permits the box and its contents to be temporarily cooled pending a repair of the cooling apparatus or otherwise arranging for the normal resumption of operation on the part of the ice mats or structures. This prevents the spoiling of 100 food or other articles inside the ice box during such abnormal conditions.

In Fig. 4 there is shown an outlet connection 105 for preventing an overflow of the cooling fluid in the circulatory pipes 4. In this arrangement the outlet pipe 7 is terminated at 7a about the middle of the bore of the pipe 4 so that cooling fluid will always tend to flow down pipe 7 when the pipes 4 are about half full. 110

This apparatus is related to that shown and covered in my United States Patent No. 1,514,128 issued November 4th, 1924.

What I claim is:

- 5 1. In a device of the class specified, the combination of a cooling support provided with refrigerating means in combination with a support comprising a spaced rack-like structure for a cooling medium above said cooling support.
- 10 2. A portable refrigerator of the class described comprising a rectangular box, a door in a wall thereof for inserting articles therein, an ice mat arranged above said door, said ice mat comprising a plurality of metallic tank-like structures having a sand mixture therein, a piping arranged within said tanks within which a cooling medium may be circulated, a plurality of drip
- 15

pans below said tank-like structures, said tank-like structures and said pans being spaced from the walls and from each other and a shelf thereabove.

3. A portable refrigerator of the class described 80 comprising a rectangular box, a door in a wall thereof for inserting articles therein, an ice mat arranged above said door, said ice mat comprising a plurality of metallic tank-like structures having a sand mixture therein, a piping arranged within said tanks within which a cooling medium may be circulated, a plurality of drip pans below 85 said tank-like structures, said tank-like structures and said pans being spaced from the walls and from each other and a shelf thereabove upon 90 which a cooling medium may be placed.
